TIRE

Arthur L. Finley, Akron, Ohio, assignor to The Goodyear
Tire & Rubber Company, Akron, Ohio

Filed Mar. 28, 1974, Ser. No. 455,681

Term of patent 14 years

Int. Cl. D12—15

U.S. Cl. D12—143

The figure is a perspective view of a tire showing my new design, it being understood that the design is repeated throughout the circumference of the tire as shown schematically by solid lines, the opposite side being substantially the same as that shown.

I claim:

The ornamental design for a tire, substantially as shown and described.
